UNITED STATES PATENT OFFICE.

WILLIAM C. ROBINSON, OF PITTSBURGH, PENNSYLVANIA, ASSIGNOR TO NATIONAL METAL MOLDING COMPANY, OF PITTSBURGH, PENNSYLVANIA, A CORPORATION OF PENNSYLVANIA.

FLEXIBLE ELECTRICAL CONDUIT.

1,203,788.

Specification of Letters Patent.

Patented Nov. 7, 1916.

Application filed June 3, 1912. Serial No. 701,315.

To all whom it may concern:

Be it known that I, WILLIAM C. ROBINSON, residing at Pittsburgh, in the county of Allegheny and State of Pennsylvania, a citizen of the United States, have invented or discovered certain new and useful Improvements in Flexible Electrical Conduits, of which improvements the following is a specification.

10 The present invention is an improvement upon that described in United States Letters Patent No. 652,806.

In the accompanying drawings Figure 1 is a view, partly in section, of a section 15 of conduit embodying the invention. Fig. 2 represents (on a larger scale) a strand of paper or like material formed of strips twisted together. Fig. 3 is a cross-section of the twisted circular strand on the line

20 III—III of Fig. 2. Fig. 4 includes enlarged views in plan and in cross-section of the flattened strip which is used as the "semi-flexible" member of the conduit.

In order to form the "semi-flexible" member 25 of the conduit I crumple and twist together a number of strips of thin paper or a similar material as generally indicated at 1 in Fig. 2. A single strip of paper of sufficient width may be so twisted, and if 30 desired the strip or strips may have applied to them an insulating varnish or sizing.

This forms a twisted strand which is circular in cross-section, as shown in Fig. 3. Then I flatten the twisted strand in any suitable way, as by passing it between pressure rollers, thus forming a comparatively thin strip, shown in Fig. 4, which I have found possesses the necessary firmness and strength for use in a conduit in the manner described in the Letters Patent above referred to. It possesses the advantages over the helically coiled member of the said Letters Patent, that while quite firm and strong, it is also relatively thin and of light weight. Having formed this "semi-flexible" strip 1, 40 I proceed to coil it helically as shown in Fig. 1 of the accompanying drawings, and then interweave with said strip strands 2 of thread, yarn or any similar flexible material. 45

I claim as my invention:

A conduit consisting of a helix formed of a flat strand of twisted paper, in combination with flexible material interwoven therewith. 50

In testimony whereof I have hereunto set my hand.

WILLIAM C. ROBINSON.
